UNITED STATES PATENT OFFICE

2,143,381

APPAREL AND PARTS THEREOF

Jay H. Lind, Brooklyn, N. Y.

Application December 23, 1936, Serial No. 117,266

5 Claims. (Cl. 2—131)

This invention relates to improvements in articles of wearing apparel, such as, for example, collars, cuffs, neckbands, etc., and more particularly, to collars of the soft-turnover type attachably or detachably applied to a shirt.

It is an object of the present invention to provide practical, economical, convenient and efficient means for maintaining, particularly, the front or wing portions of the folded-over element 10 of a soft collar firm, unwrinkled and uncurled.

It is a further object of the invention to provide apparel collars of the soft or turnover type (commonly used with men's shirts of the negligee type) with a concealed or substantially concealed 15 line of metallic stitching to render the collar more durable, firm, wrinkleproof and uncurling.

It is a further object of this invention to provide a soft fold-over collar which, while embodying all of the advantages of the ordinary soft 20 collar, overcomes the disadvantages, now generally inherent in these collars, of sagging and wrinkling in front, and thus becoming unsightly. The present invention overcomes these disadvantages in a simple, economical and efficient manner by substituting for the conventional inner 25 and concealed line of cotton-thread stitching, a resilient, flexible, durable and relatively stiff metal wire stitching or seam.

My invention is applicable for preventing an 30 article of wearing apparel to which it is applied, as for example, a collar, cuff, collar band, or shirt front from curling, wrinkling, bulging or otherwise losing its shape and neat appearance obtained when freshly laundered.

An article incorporating my invention possesses a high degree of flexibility combined with 35 desired stiffness and has imparted thereto qualities which render it springy and capable of bending at the edges without permanently creasing 40 or bending; maintenance of shape and a starched, neat and dressy appearance without the rigidity and discomfort incident to the use of starch. Heretofore, many attempts have been made to obtain the aforesaid characteristics but usually 45 at the expense of making the collar, etc., too bulky and difficult to launder, or of using a cementitious or cementitiously-coated lining or interlining which although making the same waterproof, renders it non-porous thereby preventing free circulation 50 of air through the article and free breathing of the skin in contact with the article required to keep the wearer cool and comfortable at all times.

It is a further object of this invention to provide 55 portions of a garment, such as, for example,

shirt collars, cuffs, neckbands, which may be of a light, net-like, woven or other porous construction and yet maintain its predetermined flexibility, style, shape and neatness under stress of wear and laundering without the use of stiffening 5 mediums, such as, for example, starch or rubber, cellulosic or other cementitious compounds.

It is a further object of this invention to construct portions of garments, such as, collars, cuffs, neckbands, etc., with a metal stitching or a 10 stitching having the characteristics of metal adding to the latter the desired stiffness without sacrifice of flexibility and still leaving the same of a light construction and permeability which will not interfere with free breathing of the skin 15 against which the portion of the garment is worn; which as to such article may be washed and ironed, and starched if desired; and which may be worn as an unstarched article and as 20 comfortable, being permeable to moisture, gases and vapors.

It is a further object of this invention to utilize wires, metallic or metal threads or yarn which will not corrode or rust or otherwise be affected by laundering or wearing.

It is a further object of the present invention to incorporate my improvement in a folded article of wearing apparel with the use of existing manufacturing facilities, so that the same may be done in a routine manner.

These and further objects and advantages of the invention will appear from the following disclosure thereof together with the attached drawings which illustrates certain forms or embodiments thereof, and in which:

Fig. 1 is a view of the fold-over element of a collar in the process of manufacture embodying the invention and before the same is turned inside out.

Fig. 2 is a view similar to Fig. 1, but showing 40 the fold-over element in correct condition to be applied to the neckband portion of the collar.

Fig. 3 is a view of part of the fold-over element of a collar indicating the invention in a modified form.

Fig. 4 is a sectional view taken along lines 4—4 of Fig. 2.

Fig. 5 is a sectional view of a collar embodying the invention.

As heretofore stated the invention has reference to such articles of wearing apparel, such as, for example, collars, neckbands, cuffs, shirt fronts, etc. Its application being substantially the same in all such articles, as an example, and for purposes of illustration only, it will be de- 50 55

scribed with relation to a collar of the soft turn-over type.

The collar may be of the attached or detached type, that is, one adapted to be secured to a shirt 5 (not shown) or a separate collar with its own neckband adapted to be interchangeably worn with a shirt.

The fold-over member 10 comprises the outer 10 layers 11 and the lining or interlining, as an intermediate layer 12. Fig. 1 shows the conventional arrangement of the fold-over member 10 of the collar in the process of manufacture and prior to the same being turned inside out. In 15 this arrangement, the layers 11 (which become the outer layers) are in superposed relation and the interlining 12 on top of one of the layers 11. The three layers are then secured together. Heretofore, it was customary to secure these three 20 layers together along their marginal edges 13 with cotton or similar thread.

According to this invention this seam or attachment of the three layers is produced by employing a flexible metallic thread or wire 14. The wire or metal thread 14 selected for this 25 purpose must be of the non-rust or non-corrosive type and capable of withstanding laundering, such as, for example, Monel metal, stainless steel, nickel chromium, etc. It is preferable to use cotton covered or other textile covered wire or 30 metal thread.

After the layers have been stitched together with the metal thread 14, the member 10 is turned inside out, providing the folded-in margins 13 and thus locating the rough edges 13' therewithin and between one of the outer layers 11 and interlining 12 and concealing or substantially concealing the metal thread 14, as clearly shown in 35 Fig. 2.

The wire stitching 14 will now be located very 40 close to the finished edge. A marginal line of stitching 16 is now provided in the conventional manner and with the conventional thread.

By this invention a very smooth appearing, 45 non-curling, non-wrinkling edge 15 (Fig. 4) is produced. The collar is flexible and will retain its shape and will not curl nor wrinkle. It will maintain its flexibility, style, shape and neatness under stress of wear and laundering without the use of stiffening mediums, and will give the general appearance of a starched collar.

Referring to Fig. 3 (which shows a partial view of a two ply collar), if it is desired, the front edges 17 only or the front edges 17 and corners 18 may be seamed with the metal thread and the 50 remaining part of the collar stitched with the conventional thread 19.

As shown in Fig. 5, the collar 10' may also be provided with a metal-thread seam 20 adjacent the fold line 21, that is where the fold-over mem-

ber joins the neckband 22. This will materially prevent rumpling or wilting of the collar at the fold line from moisture or perspiration, when worn.

In the accompanying drawing I have illustrated 5 the invention embodied in some practical commercial forms but as this illustration is primarily for purposes of disclosure it will be understood that the invention is not limited to these particular forms of structure and that it may be 10 modified in many respects without departure from the true spirit and scope of the invention as herein defined and claimed.

I wish it further understood that the terms which I have employed herein are used in a descriptive rather than in a limiting sense, except however for such limitations that may be imposed by the state of the prior art.

Having thus described my invention, what I claim as new and desire to secure by Letters Patent, is:

1. An article of wearing apparel having a fold-over member, said member comprising a plurality of plies having folded-in margins, a line of metal stitches joining together the plies at their 25 margins and located between the plies, and a line of stitches securing together the plies and their margins.

2. An article of wearing apparel having a fold-over member, said member comprising a plurality 30 of plies having folded-in margins, and a line of flexible non-corrosive metallic stitching joining together the plies at their margins and located between the plies whereby the plies are flexibly stiffened in the vicinity thereof.

3. An article of wearing apparel having a fold-over member, said member comprising a plurality of plies having folded-in margins, a line of flexible non-corrosive metallic stitching joining together the plies at their margins and located 40 between the plies whereby the plies are flexibly stiffened in the vicinity thereof, and a line of stitches securing together the plies and their margins.

4. A collar of the turnover type comprising a 45 neckband, a fold-over member joined thereto, and a line of corrosion-resisting metal stitching adjacent the juncture of the member and the neckband.

5. A collar of the soft turnover type comprising 50 a neckband, a foldover member joined thereto, a line of metal stitching adjacent the juncture of the member and the neckband; said member comprising a plurality of plies of fabric having folded-in edges between the plies, and a line of metal stitching joining together the said plies adjacent the edges.

JAY H. LIND.
